INVENTOR:

Max Gehre,
By his Attorneys:

Arthur T. Frane # UNITED STATES PATENT OFFICE.

MAX GEHRE, OF RATH, NEAR DUSSELDORF, GERMANY.

STEAM-METER.

SPECIFICATION forming part of Letters Patent No. 687,477, dated November 26, 1901.

Application filed July 13, 1900. Serial No. 23,434. (No model.)

To all whom it may concern:

Be it known that I, MAX GEHRE, a subject of the Duke of Saxe-Anhalt, residing at Rath, near Dusseldorf, Germany, have invented certain new and useful Improvements in Apparatus for Measuring Quantities of Steam Flowing Through a Pipe; and I do hereby declare the following to be a full, clear, and exact description of the invention, such as will enable others skilled in the art to which it appertains to make and use the same.

In the ordinary apparatuses inserted in steam-pipes for measuring the quantities of steam flowing therethrough a body is provided which constricts the passage and throttles the steam, while from both sides of said body pipes or passages lead to a fixed cylinder in order to adjust a piston situated therein, which stands under the counter-pressure of a spring, according to the existing difference between the pressure in front of and behind the constriction—that is to say, in front of and behind the piston. In this adjustment a curve piece is moved in a curve, the ordinates of which represent equivalents for one portion of a formula for calculating the flow of the steam from one vessel into another. By the said curved movement a pencil is similarly moved on a paper strip, which travels regularly forward, and said pencil draws a diagram by means of a lever transmission, which by a displacement of its point of rotation may produce a suitable multiplication of the curve recorded. This diagram then corresponds to the quantity of steam withdrawn during the period of time in question. According to the present invention, in addition to the piston, which by means of the pencil records the difference of pressure, there is further provided a second piston which, according to the various pressures, serves for indicating or recording by means of a second pencil the value for another portion of the formula which depends on the pressure.

In the accompanying drawings, Figure 1 is a vertical longitudinal section of the apparatus, and Fig. 2 a diagram produced by the same.

The apparatus consists of a casing adapted to be inserted in the steam-pipe xy and having a vertical part b open above, in which a piston r is adjustably mounted, and a narrower cylinder d , mounted on the cover c of the casing, in which another piston w moves.

The part of the casing lying under the piston r , with which the part y of the pipe is connected, has a connection with the part x of the pipe, which gives passage to the steam by means of a small opening e . Through this small opening e the steam flows with diminished pressure toward the part y of the pipe and exerts a pressure from beneath on the piston r . Simultaneously steam passes through the part x of the pipe under the cover c of the casing and the smaller piston w and over the larger piston r . The rod r' of the piston r is carried upward through the cover c of the casing, a tight joint being formed by means of a stuffing-box, and is connected with the lower end of a spring t , the upper end of which is connected with the bent-over part of a support s , fixed on the cover c . The rod w' of the piston w also passes through a stuffing-box in the casing-cover c to the outside and is connected above by means of a disk w^2 with the upper end of a spring t' , which spring at its under end is connected with the bent-over part of a support s' , also fixed on the cover c of the casing. The rod r' carries a drawing-pen or pencil o and the rod w' a pencil i . Both pencils rest on a strip of paper on a diagram-drum T , which is rotated in the ordinary manner by means of a clockwork, which is not shown. There are formulas according to which the quantities of steam flowing from one vessel into another may be exactly calculated. The basic condition is a knowledge of the steam-pressure in both vessels. As an example the known formula may be taken here:

$$G = 420 F \sqrt{\frac{(P - p)}{P v}},$$

in which G is the weight of the steam escaping in a second, v is the volume in cubic centimeters per kilogram, F is the area of the steam-escape opening in square meters, P is the higher pressure, (absolute pressure,) and p the pressure of the medium surrounding the discharge-opening. The value 420 is only available for a given form of the passage. With an alteration of the form of the opening this equivalent also alters. The said opening e serves for obtaining the necessary diminution of pressure. The piston r forms an adjustable expansion-wall and records on the diagram-paper of the drum T by means of the pencil o the difference of pressure in front

of and behind it. On the diagram-papers on the O line given periods of time—for instance, hours—are suitably indicated as abscissæ. In the example shown in Fig. 2 there are twelve 5 time-divisions. The entered ordinates are also divided into separate parts $a^2 b^2 c^2 d^2$. The distances apart of these points $a^2 b^2 c^2 d^2$ represent for the one piston r the difference of pressure $P p$ of various values—for instance $a^2, .01$ atmospheres; $b, .02$ atmospheres, &c. The piston r thus shows the difference of pressure $P p$ and transmits its movement to the pencil o , which draws a diagram, the actual ordinates of which indicate the actual 10 difference of pressure $P p$ of the steam in front of and behind the narrow opening e —that is to say, above and below the piston. The parts $a^2 b^2 c^2 d^2$, &c., of the ordinates shall, however, also indicate the equivalents 15 or partial equivalents of the formula for the calculation of the quantity of steam discharged corresponding to the actual differences of pressure. The letters $a^2 b^2 c^2 d^2$ inserted in Fig. 2 are in reality replaced by the 20 corresponding figures. It should be explained that the diagram, Fig. 2, is made up of two separate strips divided along the central horizontal line A B. In obtaining this diagram the two strips are placed on the cylinder with 25 their initial points corresponding with their respective pencils. After the diagrams have been drawn the two strips are shifted to bring their corresponding time intervals into coincidence, as in Fig. 2. It will thus be seen 30 without further explanation that these figures alter with the equivalent F of the formula given—that is to say, for different apparatuses with different openings of passage other equivalents must correspondingly be inserted for $a^2 b^2 c^2 d^2$. The other part of the 35 formula given, which depends upon the pressure P —for instance, $\sqrt{\frac{1}{v}}$, corresponding on the 40 various pressures—will be indicated on a diagram in the same manner by means of the pencil i , moved by the piston w , in which diagram then the separate heights of the ordinates $a' b' c' d'$, &c., will also be again replaced by corresponding calculated figures or 45 equivalents. It is preferable to allow the two diagrams to run off on a paper strip and so arrange the latter that the abscissæ which indicate the time coincide. The corresponding 50 equivalents can be read off from the actual positions of the pencils i and o and multiplied with one another, and thus the actual quantity of steam discharged per second be obtained. The steam consumed for any desired 55 period of time may then be calculated in the ordinary manner. The above formula may, however, be employed in various ways—for instance, by multiplying the one root equiv- 60 alent by $\sqrt{\frac{1}{v}}$ or dividing it by $\sqrt{v}$; also, the 65

factor F can be left out of the root, thus enabling the diagram formulary to be chosen equally, as it is only necessary to multiply by F the recordings of the different apparatuses.

Having now particularly described and ascertained the nature of my said invention and in what manner the same is to be performed, I declare that what I claim is—

1. An apparatus for measuring quantities of steam, having a means for restricting the flow of steam, a piston open upon one side to the higher pressure and upon the other side to the lower pressure, whereby its movements accord with the differences in pressures, and a piston upon one side to one pressure only. 75

2. An apparatus for measuring quantities of steam having a reduced passage for the steam, a piston open to the pressures upon both sides of said passage, a second piston open to pressure of steam before its reduction, 85 and means connected with said pistons for recording their movements.

3. An apparatus for measuring quantities of steam comprising a steam-passage having a reduced portion, a cylinder having openings communicating with said steam-passage at both sides of said reduced portion, a piston within said cylinder between said openings, and adapted to move in accordance with the differences in pressures upon its opposite sides, a second cylinder having an opening communicating with said steam-passage in front of said reduced portion, and a piston in 95 said cylinder adapted to move in accordance with the pressure of the unrestricted steam. 100

4. An apparatus for measuring quantities of steam comprising a steam-passage having a reduced portion, a cylinder having openings communicating with said steam-passage at both sides of said reduced portion, a piston 105 within said cylinder between said openings, and adapted to move in accordance with the differences in pressures upon its opposite sides, a second cylinder having an opening communicating with said steam-passage in front of said reduced portion, a piston in 110 said cylinder adapted to move in accordance with the pressure of the unrestricted steam, and means connected with said pistons for registering their movements. 115

5. In a steam-indicator, the arrangement of two cylinders, two pistons $r w$ each under the action of a spring, and moving in said cylinders, for measuring differences of pressure and equivalents of pressure, a recording-pencil moved by each of said pistons, the one piston w being adapted by its pencil to record the pressure, and the other piston r in a similar manner the difference of pressure. 120

In testimony whereof I affix my signature 125 in presence of two witnesses.

MAX GEHRE.
